UNITED STATES PATENT OFFICE

2,172,874

TELEPHONE SYSTEM

Arthur Robert Kahl, Coventry, England, assignor to The General Electric Company Limited, Coventry, England

Application December 16, 1936, Serial No. 116,071
In Great Britain January 23, 1936

3 Claims. (Cl. 179—5)

The present invention relates to telephone systems, and has for its object the provision of means whereby a reply to a call made by a subscriber to an operator or other callable station, 5 is not unduly delayed.

In automatic telephone systems, it is common practice for the subscriber to dial the digit "0" to obtain the services of an operator, this class of call being also used in any case of emergency. 10 As, however, the number of operators available at night is usually limited, it might easily happen that such a call remained unanswered for a considerable length of time. This should be avoided as some of the calls are of extreme urgency, such as fire, police and the like.

According to the invention a call made to an operator through an automatic exchange by the sending of a calling signal such as the digit "0", is connected to means whereby an urgent alarm 20 is given or a particular station is signalled if the call is not answered within a predetermined time and/or if the caller sends further impulses or signals without first normalising the apparatus in the circuit.

In one embodiment of the invention the single digit "0" is chosen for the purpose of calling the operator on account of its common usage by subscribers and simplicity of signalling in the darkness. The normal "0" level circuit, by which 30 the operator-directed call reaches the manual board, is amended by the provision of an impulse responding device such as a step-by-step switch and associated relay group, and also further means such as connection to a time delay circuit.

The time delay circuit and the impulse responding circuit are connected to an alarm relay individual to the "0" level circuit, this relay being operated either at the end of the predetermined time after the particular circuit has been 40 taken into use or by the sending of a further signal or signals by the subscriber.

When the said alarm relay operates, the seized "0" level circuit is connected to a multiple of 45 "urgent" jacks suitably disposed around the switchboard and in addition "urgent" visual or audible alarms may be given.

In an alternative form of circuit, means are provided in common to a group of "0" level circuits, seizure of one of the said circuits causing the selection of a digit sending apparatus which may comprise step-by-step switches, and relay groups, the said apparatus being adapted to route the call to a specific destination such as 55 a police station.

Turning now to the accompanying drawing which shows a circuit according to the invention, it will be seen that of the lines 1, 2 and 3 connected to the negative, positive and private banks respectively of exchange selectors, two terminate on a relay A which provides battery supply to the subscriber. When the latter dials a predetermined digit such as "0", his line is extended by the first selector or similar switch to the leads 1, 2 and 3, and relay A operates. So far, the practice is similar to standard as regards "0" level calls. Relay A initiates the following functions:

a₁ operates relay B. 15
a₂ prepares a loop for signalling to the operator's cord circuit later.

b₁ applies ringing tone to lead 1 and hence to the subscriber's instrument.

b₂ applies earth potential to lead 3 thus engaging the outlet to other selectors. 20

b₃ operates relay TA on one coil in series with TM but the latter, being insensitive, does not itself operate, as the operating coil of relay TA is of high resistance.

b₄ prepares to operate relay TO. 25
b₅ prepares a stepping path for the driving magnet DM.

b₆ lights the calling lamp CL to attract the attention of the operator.

b₇ prepares a locking path for relay TO. 30

t₁ connects impulse cam K to the magnet UM of a step by step switch U which is common to a number of 0 level circuits. This switch now proceeds to step at a slow rate.

If the operator replies at once or after a short period, relay S is operated by the insertion of the plug in the jack AJ, this relay performing the following functions:

s₁ extinguishes the calling lamp CL. 40
s₂ removes ring tone from the subscriber's line.

s₃ releases relay TA.

s₄ prevents additional impulsing of relay A from stepping switch D.

The operator can now attend to the requirements of the subscriber in a normal manner, release of the connection by the subscriber causing release of relays A and B, while removal of the answering plug from the jack AJ completes the normalising process on the circuit by release of relay S. Contact b₅ drives the switch D to a predetermined or "home" position by earth derived from bank D1.

If however for some reason reply to the call 55

is delayed and the subscriber dials any further digit other than 1, contact *a1* impulses the driving magnet *DM* via contact *b5*.

- Wiper *D2* now steps on to contacts connected to earth, this potential operating relay *TO* via contact *b4*. The relay locks itself operated through its own contact *to5* to contact *b1*, the remaining contacts performing the following functions:
- 5 to*1* and *to2* connect the leads **1** and **2** to an "urgent" jack *UJ* on another operator's position which is always attended.
  - 10 *to3* lights a calling lamp *UL* associated with the jack *UJ*.
  - 15 *to4* brings into operation a bell *UB* which gives an audible signal.
  - 20 *to6* extinguishes the lamp *CL* on the position on which the call first appeared.
  - 25 When the operator attends to the urgent call by plugging into the jack *UJ*, relay *SA* operates.
  - 30 *sa1* extinguishes the lamp *UL*.
  - 35 *sa2* silences the bell *UB*.
  - 40 *sa3* removes ringing tone from lead **1**.
  - 45 *sa4* releases relay *TA*.

The call is now attended to, at the end of which relays *A* and *B* release when the subscriber replaces the receiver. The switch *D* is now stepped 30 to a normal position by earth potential derived from *D1* via the self-interrupter contacts *dm* and contact *b5*.

Should the caller refrain from dialling an extra digit, then a further action takes place. The switch *U* continues to be impelled as previously described, until the wiper *U1* encounters the second contact on its bank. In this position a second low resistance winding of relay *TA* is placed in parallel with the first winding, and the relay, whilst remaining held operated, allows sufficient current to pass through it to operate *TM*, which locks in this position at its contact *tm1*. The switch continues to step until its wiper *U2* finally encounters the first contact in its bank after a delay determined by the number of contacts per bank and the rate of stepping derived from the cam *K*. When it reaches the point stated, earth from wiper *U2* is applied through contact *tm2* to one coil of relay *TO*, which operates and locks itself in this position to contact *b7*. The contacts of this relay perform functions similar to those already described and the call is transformed from a normal "0" level call into an urgent one. All subsequent operations are similar to those described for the case in which the subscriber dials an extra digit.

Although the invention has been described as

utilizing only one "urgent" jack per exchange, it is obviously not limited thereto. Methods are well known in the art whereby "urgent" calls maturing simultaneously could be arranged to appear singly on a plurality of jacks, or could utilize the same "urgent" jack in succession.

Similarly although the "urgent" calls are described as appearing on a jack attended by an operator, they could alternatively be connected directly to a line to, for example, a police or fire station, this being accomplished by means of a common impulse-sending apparatus comprising a step-by-step switch or switches and a control group of relays. Such devices are known in the art, and could easily be adapted to perform the functions required. Thus when an "0" level call became urgent, the procedure would be for the affected "0" level circuit to seize the impulse sending device which would then connect the call to normal exchange apparatus and set the latter on a predetermined number.

I claim:

1. In a telephone system, an operator's trunk circuit terminating in jacks, a signal for each jack, subscribers' lines, means controlled over 25 a subscriber's line for extending a call to said trunk circuit and always operating the signal associated with one of said jacks, and means responsive to the transmission of further impulses to the trunk circuit by the subscriber after 30 the trunk is seized for operating the second signal associated with another jack.

2. In a telephone system, an operator's position terminating in the answering jacks, calling lines, means controlled from a calling line for 35 extending a call to the position and operating a signal associated with one of said jacks, an urgent signal associated with another jack, a relay at the position, a step-by-step switch, said relay responsive to a series of impulses over a 40 calling line after the said first signal is operated for operating said switch to cause operation of the urgent signal.

3. In a telephone system, trunk circuits extending to an operator's position, calling lines, 45 means for completing calls for calling lines to said trunk circuits and signalling the operator thereat, a special operator's trunk and signal, a timing switch for switching a call to said special trunk a predetermined time after the call 50 is extended thereto if the call on the trunk circuit is not answered, and another switch controlled by the calling subscriber for promptly operating the signal at the special trunk in case of urgent calls.

ARTHUR ROBERT KAHL.
